US0D1059849S

(12) **United States Design Patent** (10) Patent No.: **US D1,059,849 S**
(45) Date of Patent: ** Feb. 4, 2025

(54) **MASCARA BRUSH**

(71) Applicant: **SOCIETE INDUSTRIELLE DE MATIERES PLASTIQUES**, Tigery (FR)

(72) Inventor: **Eric De Bardonneche**, Montaren-et-Saint Mediers (FR)

(**) Term: **15 Years**

(21) Appl. No.: **35/518,149**

(22) Filed: **Jul. 31, 2023**

(80) **Hague Agreement Data**

Int. Filing Date: **Jul. 31, 2023**

Int. Reg. No.: **DM/230809**

Int. Reg. Date: **Jul. 31, 2023**

Int. Reg. Pub. Date: **Aug. 25, 2023**

(51) **LOC (15) Cl.** **04-02**

(52) **U.S. Cl.**

USPC **D4/128**; D4/133

(58) **Field of Classification Search**

USPC D4/100, 102, 119, 120, 127, 128, 130, D4/131, 132, 133, 134, 136, 199; D28/7, D28/9, 99
